UNITED STATES PATENT OFFICE

SAFETY DEVICE FOR BREECH LOADING GUNS

William V. Goodhue, East Greenwich, R. I., and Emerson C. Gill, Saugus, Mass., assignors to United Shoe Machinery Corporation, Flemington, N. J., a corporation of New Jersey

Application September 4, 1947, Serial No. 772,167

6 Claims.

(Cl. 89—6.5)

1 This invention relates to a safety device for fuse-setting and ramming mechanisms to prevent the ramming of a round against a closed breech-block and it is herein illustrated as applied to an anti-aircraft gun having an automatic fuse-setting and ramming mechanism of the type disclosed in the application of Dabrowsky, Goodhue and Taylor, Serial No. 473,738, filed January 27, 1943, which has matured into Patent No. 2,442,401, patented June 1, 1948.

In using anti-aircraft guns which are provided with an automatic fuse-setting and ramming mechanism it is the custom for the gunner to close the breechblock manually at the end of a period of use to prevent dirt and moisture from getting into the barrel of the gun and it is necessary to insure reopening of the breechblock before it is safe to use the mechanism because of the obvious danger of ramming a shell violently against the outside of the closed breechblock and causing an explosion in the mechanism. The normal operation of the fuse-setting and ramming mechanism of the above application includes the presentation of a round to a pair of driven feed rolls which carry the shell forwardly into contact with fuse-setting jaws. These jaws stop the round and stall the feed rolls by reason of their engagement with the round. Thereafter, when the fuse has been set, the jaws are withdrawn and the round pushed forward into the gun, the breechblock closing automatically.

An object of the invention is to provide a safety device which will cooperate with the device shown in the above mentioned application to prevent malfunctioning thereof.

As herein illustrated a detent is provided which is moved into the path of the fuse-jaw-opening parts and which thus prevents the release of the shell held by the jaws and completion of the ramming movement. Associated with this detent is a linkage, the position of which depends upon the position of the breechblock and whenever the breechblock is in its open position the detent is rendered ineffective. Furthermore the arrangement is such that the detent is automatically reset as the breechblock is opened at about the beginning of counter-recoil.

These and other features of the invention will best be understood from a consideration of the following specification taken in connection with the accompanying drawings in which:

Fig. 1 is an angular view, from the left rear side of the cradle, of an antiaircraft gun, in battery position, on which there has been mounted

2 a ramming and fuse-setting mechanism having such a safety device;

Fig. 2 is a side elevation on a larger scale of means for operating a safety lock;

Fig. 3 is a vertical section on the line III—III of Fig. 2 through one side of the cradle;

Fig. 4 is a horizontal section through the feed rolls of the ramming mechanism, but showing them separated as in the position which they

10 assume when the cartridge case is being expelled; and

Fig. 5 is a vertical section through the fuse setter mechanism, showing the fuse jaws withdrawn to permit the passage of a shell to the gun.

The illustrated safety device, for preventing accidental ramming of a round of ammunition when the breechblock is closed, is shown herein as applied to an anti-aircraft gun. The barrel

20 of that gun is mounted for recoil movement in ways 12 supported in a cradle 14 which is tiltable about trunnions 16 to elevate the gun. On the barrel is a breech ring 18 in which a breechblock 20 (Fig. 2) may slide down to open the breech 25 or move up to close it. To the rear end of the breech ring a sub-frame 22 is secured by bolts 24. This sub-frame supports the round-engaging parts of a fuse-setting and ramming mechanism and recoils with the gun barrel. The ramming

30 of the ammunition is effected through a pair of driven, grooved, rubber feed rolls 26 (Fig. 4), arranged on swingable mounts 28 and provided with power for rotation through a driven shaft 30 (Fig. 1). These mounts are pivoted on the sub-frame 22. The rolls 26 are interconnected for rotation together by pinions 32 and the mounts 28 are swung inwardly to bring the rolls against the sides of a round whenever the gun is in battery position, ready to be loaded, so that a rod 34

35 engages the breech ring of the gun and resiliently urges the roll mounts inward. Upon recoil, a spring 36 operating on rod 34 through a cross piece 38 opens the rolls.

Associated with the ramming mechanism and in line with the bore of the gun is a fuse-setting mechanism which comprises a ring 40 (Fig. 5) capable of being turned about the axis of the bore of the gun to set the fuse ring of a shell. The fuse ring is engaged, when the parts are in operative position, by knives 42 mounted on jaws 44 capable of being swung inwardly by links 46 connected to a sliding, sleeve-like rank 48. This rank is slidable axially on the ring 40 and has, on its outer surface, circular rack ribs 50 engaged by

55 the teeth of a pinion 52 (Fig. 3) which is on an

upright shaft 54 journaled in the sub-frame 22. The shaft 54 carries at its upper end another pinion 56 meshing with a rack 58. This rack 58, formed as part of a block 60, is urged forwardly of the gun by a spring 62 (Figs. 1 and 2) which surrounds a rod 64 connected to the rack block 60 and one end of the spring engages a collar 66 (Fig. 1) on this rod while the other end abuts a bracket 68 on the breech ring 18. When the block 60 and the rod 64 are in the position shown in Fig. 1, the fuse jaws 44 are closed because the rod 64 will have been pushed to the rear by an operating rod 70 which is pushed out from a control box 72 by mechanism contained therein. At that time the fuse jaws are turned inwardly to a position where they catch the shell and prevent further movement of it toward the breech of the gun, whereupon the driven rolls 26 are stalled by engagement with the shell which is held from movement by the fuse setter.

Our safety mechanism is so designed that a detent 80 engages the front end of the block 60 and prevents the fuse jaws 44 from being thrown outwardly by the spring 62 to the position shown in Fig. 5 whenever the breechblock is closed. To this end the detent 80 is mounted in a grooved carrier 82 pivoted on a pin 84 supported in the bracket 68 which serves as a guide for the rod 64. This bracket, being on the breech ring 18, recoils with the gun. The forward end of the detent carrier 82 is provided with a transverse slot 84' cut back at 86 and 88 to provide a tapered entrance to that slot to facilitate the entrance, during counter-recoil, of a roll 90 which is mounted on the upper end of a vertically movable bar 92 which is down when the breechblock is in its upper and hence its closed position. This bar 92 is provided with a slot 94 so that it may move up and down on a fixed guide pin 96 which is attached to the side of the cradle 14.

The lower end of the bar 92 is pivotally connected to a bell-crank 98 mounted on a shaft 96' which is journaled in the side of the cradle and the bell-crank is urged in a counterclockwise direction by a spring 100. Inside the cradle the shaft 96' of the bell-crank 98 is provided with a long slender arm 102, the under side of which, under the action of the spring 100, bears against the pin 104 of a crank 106 which is mounted to rotate with a shaft 108 which carries an operating arm (not shown) for raising the breechblock 20. The crank 106 is used for automatically opening the breechblock during counter-recoil as will be later described. The detent carrier 82 is normally moved in a clockwise direction by a spring 110 interposed between said carrier and a cup-shaped lug 112 on the bracket 68. Thus, because of the springs 100 and 110, the slender crank arm 102 can never interfere with the operation of the breechblock, and the roll 90 on the upper end of the vertically slideable bar 92 can never break the carrier 82 whatever the position of the detent 80 may be. The detent 80 is normally spring-pressed upwardly against the bottom of the rack block 60 by an internally mounted spring 114 positioned between the under side of the detent 80 and a horizontal portion of the carrier 82 but its movement is limited by the engagement of a tail-piece 116 on the detent with a ledge 118 on the carrier 82.

In a gun of this type, the operation of the breechblock 20 is normally automatic. The breechblock is closed initially, as a round enters the gun, by engagement of a flange 120 (Fig. 4) on the rear end of a cartridge case 122 with the

extractors (not shown) thus releasing a latch and allowing a spring to raise the breechblock. When this happens the crank 106 of Fig. 2 will assume its dot and dash position and, as the gun recoils, the crank pin 104 will travel along the cradle above the upper edge of a strip 124 attached to that cradle by means of bolts 126. At the rear end of this strip there is an automatic breech-opening cam 128 pivoted on the inside of the cradle which is deflected by the crank pin and then springs back into position in front of that crank pin as the gun reaches its rearmost position. Then as the gun starts on counter-recoil the crank pin will engage the rear edge 130 of the opening cam 128 and will be caused to slide downwardly turning the crank so as to open the breechblock. The crank pin will follow along the under side 132 of the strip 124 as the gun moves back to battery position.

It will be understood that, after the gun has been fired, the control rod 70 will be moved rearwardly by mechanism contained within the control box 72 and will cause the rod 64 and the block 60 to be moved rearwardly thereby to move the fuse jaws to their inner position as the gun moves forwardly into battery position during counter-recoil. At that time the breechblock 20 will be in its lowered position corresponding to the full line position of the crank 106. The arm 102 attached to the crank 98 will then be in its full line position and the sliding bar 92 will be raised releasing the detent 80 for the next loading and firing cycle.

However, if the breech has been closed manually by a hand lever (not shown), which is on the far side of the cradle as viewed in Fig. 2 and which is attached to the crank shaft 108, then the long thin arm 102 will be raised to its dot and dash position and will draw down the bar 92 and the roll 90 thus tilting the detent carrier 82 and moving the detent 80 to its upper position. This will prevent the spring 62 from moving forward the rod 64 attached to the rack block 60, if the rod 70 were to be pulled into the control box 72, and thus will prevent the fuse-setting jaws 44 from being moved outwardly to the position shown in Fig. 5. In their inner position, these jaws are braced on the radially positioned links 46 and prevent the round of ammunition from moving beyond them toward the breechblock and thereby prevent any accidental engagement of the round with that block.

Having thus described our invention, what we claim as new and desire to secure by Letters Patent of the United States is:

1. In combination, a breech-loading gun having a displaceable breechblock, a ramming mechanism for delivering a round of ammunition to the gun, a stop to interrupt the movement of the round before it reaches the breechblock, means for releasing said stop, a detent to prevent release of the stop, and means responsive to the position of the breechblock to move the detent into and out of operative relation to the stop-releasing means.

2. In combination, a breech-loading gun having a displaceable breechblock, a ramming mechanism therefor, means for stopping the round carried forward by the ramming mechanism, said means being movable into the path of the round to engage it, means for moving said stopping means out of the path of the round, a detent for said moving means, and means for moving said detent into the path of said moving means when the breechblock is closed.

3. In combination, a support, a breech-loading gun mounted for recoil with respect to the support, a displaceable breechblock on the gun, automatic mechanism to open the breechblock during counter-recoil, operator controlled mechanism for closing the breechblock, a fuse setter adjacent to the breech of the gun, said fuse setter having a member movable into engagement with the round to stop it and maintain it in that position during the fuse-setting operation, a ramming mechanism alined with the fuse setter, movable means for withdrawing the fuse setter stop member, a detent engaging said withdrawing means, and means responsive to the position of the breechblock to move the detent into and out of the path of the stop-withdrawing means.

4. In combination, a support, a breech-loading gun mounted for recoil with respect to the support, a displaceable breechblock on the gun, automatic mechanism to open the breechblock during counter-recoil, operator-controlled mechanism for closing the breechblock, a fuse setter adjacent to the breech of the gun, said fuse setter having a member movable into engagement with the round to stop it and maintain it in that position during the fuse-setting operation, a ramming mechanism alined with the fuse setter, movable means for withdrawing the fuse setter stop member, a detent engaging said withdrawing means, means responsive to the position of the breechblock to move the detent into and out of the path

of the stop-withdrawing means, and a confection between the breechblock and said detent to position the latter in accordance with the position of the breechblock.

5. In combination, a gun cradle, a gun slidably mounted thereon for recoil movement, a fuse-setting mechanism mounted on the gun and arranged for operation upon a round moving along a path alined with the bore of the gun, said fuse-setting mechanism including a round-engaging stop, movable means on the gun for withdrawing said stop, a detent on the gun movable into and out of the path of movement of said stop moving means, said detent being provided with a forked end, a member movably mounted on the cradle having a portion to enter the forked end of the detent, and a connection between the said member and the breechblock to position the member in accordance with the position of the breechblock.

6. A mechanism as in claim 5 in which the detent comprises a pivoted carrier forked at one end and grooved at the other, a pawl in said grooved portion, a spring to move the pawl out of the groove, and a stop to limit the outward movement of the pawl.

WILLIAM V. GOODHUE.
